UNITED STATES PATENT OFFICE

2,526,927

ROLLING AND ROCKING TOY

Robert B. Bennett, Akron, Ohio

Application December 6, 1946, Serial No. 714,369

4 Claims. (Cl. 280—30)

This invention relates to improvements in rolling and rocking toys, and more particularly to a roller toy which is convertible to a stroller, or which may be converted into a rocking toy.

It is the object of this invention to provide an enclosed rolling toy, with seat, steering means, and foot rests, wherein the latter may be adjusted to permit the occupant's feet to engage the ground.

It is the object of this invention to provide means whereby the toy is upsettable 180° to produce a rocking toy with seat together with means for limiting rocking movements.

It is the further object of this invention to provide the rolling toy with a storage compartment, and with a bumper mechanism positioned entirely around the toy and joined to the closure door of said compartment.

It is a still further object of this invention to provide means for upwardly tilting said bumper so that the same may be employed as a handle for pushing the rolling toy as a stroller.

These and many other objects will be seen in the following specification and claims in conjunction with the appended drawings in which:

Figure 1 is a plan view of the rolling toy.

Figure 2 is a side elevational section thereof on line 2—2 of Figure 1.

Figure 3 is a front elevational section thereof on line 3—3 of Figure 2.

Figure 4 is a front elevational section thereof on line 4—4 of Figure 2, and

Figure 5 is a fragmentary view of the rolling toy with bumper pivoted upwardly and compartment cover opened.

It will be understood that the above drawings illustrate merely one preferred embodiment of the invention, and that other embodiments are contemplated within the scope of the claims hereafter set out.

Referring to the drawing, the rolling toy comprises a substantially U-shaped base frame consisting of spaced converging side members 11, central front end member 12, and cross bars 13 and 14. Said members are preferably of hollow tubular construction for lightness and strength. Said forward end member 12 extends outwardly at its ends and curves rearwardly at points 15 with its rear portions 16 bent inwardly as best illustrated in Figure 1.

Cross bars 13 and 14 join side members 11 at their ends to reinforce the base structure of the toy.

Referring to Figure 3 front support 12 has mounted and welded thereon at points 18 the two

spaced upwardly and rearwardly curved arcuate supports 19 with reinforcing cross bar 20 joined thereto. Spaced members 19 are substantially semicircular as shown in Figure 2, project upwardly and back, and beyond their central highest portion are curved downwardly with their respective ends suitably joined to the ends of cross bar 17 as illustrated in Figures 1 and 2.

Spacer bars 21, 22, 23 and 24 are interposed between arcuate members 19 and respectively secured thereto at their ends as by welding to provide a rigid structure.

Spaced cockpit forming guard rails 25 are positioned below the highest portions of arcuate rocker members 19 and supported by inwardly projecting extensions 26 interposed between said rails and members 19. The inwardly curved ends of rails 25 are respectively joined to cross bars 22 and 23 to provide a closed cockpit.

Flat back rest 27—28, Figures 1 and 2, is interposed between rocker members 19 at its upper portion 27 and extends angularly downward and diverges.

The lower portion of said back rest extends downwardly at an obtuse angle to portion 27 and is suitably secured at its lower end to cross bar 14.

Horizontal seat 29 is elevated relative to base 11—12 and is joined and secured at one end to an intermediate portion of back rest 27—28 by screws 30. The forward portion 31 of said seat, of reduced width to accommodate the rider's legs, extends forwardly and is secured and supported at its other end to cross bar 20 by clip bracket 32 and bolt 33.

When employed as a rocking toy being upset 180 degrees to rest on the arcuate edges of members 19, it is seen that the same seat 29 may be used upon its other surface in conjunction with back rest 28.

Member 31 has a forward enlarged portion 32' with a central opening therein through which steering bushing 33' is rotatably journaled. Supporting discs 34 having corresponding openings therein are positioned above and below portion 32' and secured thereto by screws or rivets 35 to more effectively journal and support said steering bushing.

Front wheel supporting fork 36 is aligned with bushing 33' which centrally projects thereinto and is secured thereto as by welding at points 37. Wheel axle supporting clips 38 are bolted at 39 to the lower ends of fork 36 to support axle 39 upon which front wheel 40 is journaled.

Steering shaft 41 projects down into bushing

33' and is secured relatively thereto by collar 42 with set screw 43. Said shaft projects upwardly and terminates in the steering wheel segment 44 as illustrated in Figure 1.

Referring to Figures 1 and 2 rear axle supporting plate 45 extends between cross bars 14 and 17 with its forward edge 46 upturned and suitably secured upon bar 14 as by welding, and with its rear edge 47 formed to engage the underside of cross bar 17 to which it is preferably welded.

Plate 45 has a furrowed or arcuate transverse depression within which is mounted rear axle 48, and which is retained therein by the formed brackets 49 held in position by rivets 50.

Axle 48 projects beyond plate 45 and rear wheels 51 are suitably journaled and retained thereon to support the rear end of the rolling toy.

The vehicle bumper consists of a formed unitary member preferably of tubular construction 51' which is completed enclosed in a resilient substance 52 such as rubber to act as a cushion.

Said bumper which is adapted to entirely surround the toy consists of the diverging side members 53 which are pivotally mounted at their rear ends to the outer ends of axle 48. The ends of members 53 are formed to curve downwardly at points 54 and inwardly, and are joined by intermediate end bumper member 55. Similarly the front ends of said bumper members 53 are curved downwardly at points 56 and inwardly, being joined by intermediate front end bumper member 57. It will be noted that said bumper in surrounding the vehicle corresponds in shape with and lies in parallel relation to members 11, 15, 12 and 17 respectively, forming a part of the vehicle base.

As illustrated in Figures 1 and 2 the front and rear bumper portions 57 and 55 are positioned relatively close to the surface upon which the toy is rolled, to thereby push movable obstacles such as feet, furniture or toys to one side rather than running over them. Said bumpers are adapted to prevent tipping of the toy and also protect the walls of a room since they are positioned to strike the more scar resistant base board.

The front end of the toy bumper is normally horizontally supported by the spaced clips 58 which are secured at points 59 to opposite sides of the front end of the toy.

As illustrated in Figures 1, 2 and 4 floor boards 60 and 61 are respectively hinged at 62 and 63 to the inner edges of said frame members 11 and rest in horizontal position upon cross support 13, Figure 1, to act as a foot rest for the occupant when the toy is in strolling position.

When the rolling toy is to be used as a walker, floor boards 60 and 61 may be pivoted upwardly, Figure 4, to a vertical position with their upper ends retained against falling by spring clips 64, secured at 65 to the inner side walls of the toy.

Similarly, when the toy is inverted 180 degrees to be used as a rocking toy members 60 and 61 would normally be positioned vertically, though it is not absolutely essential inasmuch as there is a definite spaced relation between the edges of members 60 and 61 and back rest 28.

The frame work of the toy is completely enclosed by a covering shell or skin 66 which in Figure 3 is shown as extending across the front end of the toy with its central portions bearing upon the two spaced arcuate members 19 and with its side portions extending down and outwardly from said members and joined at 67 to the underside of frame member 11. The front

portion of shell 66 extends along the outer edges of arcuate members 19 and is also joined at 67 to the undersides of front frame member 12.

Side shell members 66 as shown in Figure 4 extend only to the top edge of the central effective rocking portion of arcuate members 19 as further illustrated in Figure 1.

The rear portion of the toy could be further covered by shell 66 if desired to make the toy 10 fully enclosed as a unit. However, in the present embodiment a compartment is provided at the rear of the toy to allow transportation of articles such as groceries, in the manner illustrated in Figure 5.

15 Referring to Figures 1, 2 and 5 it is seen that the compartment 68 is outlined by the edges of converging rear portions of shell 66, Figure 5, and the spaced downwardly curved arcuate members 19.

20 A hollow storage container is provided for this compartment consisting of platform base 69 which may be omitted if desired, shell side members 70 and intermediate top shell member 71. Container 70, 71 is positioned over spaced arcuate members 19 and pivotally joined thereto on opposite sides at points 72 on the inner supports of side members 70. In the closed position Figure 2 container platform 69 rests at its forward edge upon cross brace 14, while the under side of curved top wall 71 rests upon arcuate members 19.

25 Referring to Figures 1 and 5 spaced levers 73 are pivotally joined at their outer ends at points 74 to outer portions of rear bumper member 55.

30 The inner ends of said levers project up through openings 75 in the bottom of platform 69 adjacent side walls 70.

35 Links 76 are pivotally joined at one of their ends at 77 to the inner ends of said levers respectively, with their forward ends being pivotally joined at 78 to the inner side walls 70 of the storage container.

40 Thus, bumper 53, 55, 57 may be pivoted about its supporting axis 48 to the position shown in Figure 5 to act as a handle for the toy when used as a push cart or a stroller. Said bumper is limited in its pivotal movement by its lower end 55 engaging the inner ends of frame members 11, Figure 5.

45 Referring to Figure 2 when the toy is inverted 180 degrees to rest upon rocker members 19, portions 79 and 80 forming a part thereof are substantially flat to limit the rocking arc of the toy to prevent accidental tipping. Extreme

50 rocking movements are further limited by the front and rear portions 55 and 57 of the toy bumper.

55 As viewed in Figure 1, the rear portions of container 70 at its opposite sides are cut away at 81 adjacent pivotal support 72 to provide a clearance for said container relative to arcuate members 19 when said container is pivoted to the position shown in Figure 5.

Having described my invention, reference 60 should now be had to the claims which follow for determining the scope thereof.

I claim:

65 1. A rolling and rocking toy comprising a hollow base, spaced supporting wheels journaled thereon a pair of spaced arcuate upwardly extending rocker members mounted on said base and joined thereto at their ends, a continuous bumper positioned entirely around said base and rearwardly pivoted thereon, being adapted to 70 upward pivoting whereby the front portion of

said bumper may be employed as a handle for pushing the toy, and a pair of inwardly projecting floor boards hinged at their outer edges to said base and adapted to be pivoted into parallel alignment with said arcuate members.

2. A rolling and rocking toy comprising a hollow base, spaced supporting wheels journaled thereon a pair of spaced arcuate upwardly extending rocker members mounted on said base and joined thereto at their ends, a continuous bumper positioned entirely around said base and rearwardly pivoted thereon, being adapted to upward pivoting whereby the front portion of said bumper may be employed as a handle for pushing the toy, a pair of inwardly projecting floor boards hinged at their outer edges to said base and adapted to be pivoted into parallel alignment with said arcuate members, formed toy enclosing sidewall members extending from said base and over a substantial portion of said rocker members, and spring clips on the interior of said wall members for securing said floor boards in the latter position.

3. A rolling and rocking toy comprising a hollow base, a pair of spaced arcuate upwardly extending rocker members mounted on said base, a centrally converging back rest positioned between said rocker members, a seat member secured at one end to the apex portion of said back rest, and with its elongated forward portion being secured to said arcuate members, a central steering wheel rotatably journaled and supported from said elongated portion, a rear platform on said base and having a transverse

arcuate trough formed therein, a rear axle mounted on said platform within said trough, and a pair of wheels journaled on opposite ends of said axle.

5. A rolling and rocking toy comprising a hollow base, a pair of spaced arcuate upwardly extending rocker members mounted on said base, a centrally converging back rest positioned between said rocker members, a seat member secured at one end to the apex portion of said back rest, and with its elongated forward portion being secured to said arcuate members, a central steering wheel rotatably journaled and supported from said elongated portion, a rear platform on said base, a rear axle mounted on said platform, with a pair of wheels on its ends, and a continuous bumper positioned entirely around said base and rearwardly pivoted to the ends of said axle, being adapted to upward pivoting whereby said bumper acts as a handle for pushing the toy.

ROBERT B. BENNETT.
